UNITED STATES PATENT OFFICE.

CHARLES FLETCHER, OF PROVIDENCE, RHODE ISLAND.

MACHINE FOR COMBING WOOL, &c.

SPECIFICATION forming part of Letters Patent No. 271,825, dated January 30, 1883.

Application filed March 10, 1882. (No model.)

To all whom it may concern:

Be it known that I, CHARLES FLETCHER, of the city of Providence, in the State of Rhode Island, have invented a new and useful Improvement in Machines for Combing Wool, &c., of which the following is a specification.

My invention relates to that class of machines, known as "combing," "carding," and "drawing" machines, for preparing the sliver of wool fiber. In such machines front and back draft-rolls have heretofore been used in a well-known manner, and an apron has been used with and passing between the front draft-rolls in a well-known manner, to aid in the drawing process, such apron having been constructed with a seam or joining across it where the ends were brought together.

My invention consists in making this apron endless and seamless transversely of it, and using and applying it in the same place and position as before in the machine, substantially so as to constitute a combination of the apron with its co-operating rolls, substantially as hereinafter described and claimed; and the principle upon which it operates is that, because there is no such joint or seam in such apron, the fiber, in passing through between such apron and the draft-roll pressing upon it and against the other roll, will grasp and draw the fiber evenly at all parts of the impact of the apron against it, because all parts of the apron passing between the draft-rolls are of substantially the same texture and elasticity, owing to the manner in which I construct it, as described. Besides, the grease or oil expressed from the fiber while passing between the draft-roll and apron does not operate to destroy the apron for use by penetrating into and acting upon to harden or destroy any glue, cement, or joining material used to unite the ends of the apron in a suitable manner for use with such draft-rolls, because there is no such joining of ends and consequent joining material used with my apron upon which it can act. It is of course understood and well known in practice that the apron passes between the draft-rolls under tension, and that this tension must be greater to promote its effective operation the harder and less elastic the material of the apron is, and if any part of an apron is harder and less elastic than another the tension necessarily applied to the entire apron

to cause it to work effectively at these harder parts is greater than is necessary for the effective operation of the more elastic parts of the apron; and as any practicable joint formed by the uniting of the ends of such apron is necessarily much harder and less elastic than the other parts, it is obvious that my seamless apron requires less tension to cause it to work effectively and evenly in drawing the fiber in all its parts than a jointed apron, and this enables the entire machine to be operated with less power and wear of parts.

Having thus described the principle upon which my invention operates, I will now proceed to describe its construction as used upon a wool-combing machine.

The drawing represents the draft-rolls of a combing-machine and adjacent parts of the machine to which my invention is applied.

A A are the front draft-rolls of the combing-machine. D D are the back draft-rolls. E are the faller-gills. The fiber passes first through the back draft-rollers, thence over the faller-gills, and thence between the front draft-rollers, which run at such a relative speed as to draw out the sliver as it passes through them. These parts of the machine are well known and of the ordinary construction, and need no further description to be understood. The other parts of the machine to which they are connected are also of the ordinary construction and well known, and therefore are not shown in the drawing.

At some distance below the lower draft-roll A, and parallel thereto, is mounted the roller B, of equal length with the former. Around the lower roller A and the roller B is passed the endless apron C, which has a breadth equal to the length of these rolls, and is pressed upon by the upper draft-roll as it passes the nip of that and the lower one. This causes the apron to traverse continuously around the roller B, which is allowed to revolve freely for that purpose, and to present constantly a different part of the apron to the nip of the rolls A A. The fiber to be drawn out passes between the upper draft-roll A and the surface of the traversing apron C, thus forming an elastic grip upon the fiber, which is necessary to properly draw it out. The apron C is made of endless material, so as to have no seam or joining across its breadth. It thus presents

between the rolls A A a substantially-uniform structure at all points of its traverse, which takes hold of the fiber constantly pressed against it at all points alike, and thus draws it out with the greatest degree of evenness and regularity, which is essential to the perfect preparation of the sliver. After passing the rolls A A and apron C the sliver may be either conducted to a can or into other parts of the machine, to be further operated upon, according to its construction.

What I claim as new and of my invention is—

In combination with the drawing-rolls A A, the endless traveling cushion or apron C, passing between them, formed of an endless piece of material without joining or seam, substantially as described.

CHARLES FLETCHER.
